UNITED STATES PATENT OFFICE.

WILLIAM A. GILL, OF PORTLAND, OREGON.

CARBURETER FOR EXPLOSIVE-ENGINES.

SPECIFICATION forming part of Letters Patent No. 734,848, dated July 28, 1903.

Application filed April 10, 1902. Serial No. 102,269. (No model.)

To all whom it may concern:

Be it known that I, WILLIAM A. GILL, a citizen of the United States, residing at Portland, in the county of Multnomah and State of Oregon, have invented certain new and useful Improvements in Carbureters for Explosive-Engines; and I do declare the following to be a full, clear, and exact description of the invention, such as will enable others skilled in the art to which it appertains to make and use the same.

This invention relates to means for mixing and regulating the supply of air and a liquid fuel, such as gasoline or any other suitable volatile oil or hydrocarbon, to the cylinders of explosive-engines, and has for its object to provide a feeding and mixing device which is simple of construction, reliable and efficient in operation, and designed to preserve definite relations in the proportions of the air and vapor forming the explosive mixture and greater homogeneity in the admixture, thereby obtaining increased efficiency in the working of the engine.

25 The invention consists of certain novel features and parts and combinations of the same, as will be fully described hereinafter and then pointed out in the claims.

A practical embodiment of the invention is 30 represented in the accompanying drawings, in which similar characters of reference indicate corresponding parts in all the views.

Figure 1 is a central vertical section of a feed-cup and mixer embodying my invention. 35 Fig. 2 is a similar section taken at right angles to that shown in Fig. 1. Fig. 3 is a face view of the hand wheel or disk of the feed-valve.

Referring now more particularly to the drawings, the numeral 1 represents an outer 40 casing or shell, within which is concentrically disposed a vertical tube 2, forming with suitable top and bottom caps 3 and 4 a feed-cup or reservoir 5 to hold a definite supply of liquid fuel, and a mixing chamber or passage 6, in 45 which the fuel is commingled with air to produce the explosive mixture. The tube 2 extends downward through the cap 3 and is formed at its upper end with a head or shoulder 7 to rest thereon and threaded at its lower 50 end 8 to engage a threaded flange 8^a, rising from the cap 4, whereby the parts are united and the shell 1 clamped between the caps.

Packing-rings 9 are interposed between both caps and the upper and lower ends of the shell 1 and between the bottom cap and lower end 55 of the tube 2 to make the joints air and liquid tight. Preferably the shell 1 is made of glass or some other suitable transparent material to enable the interior of the reservoir 5 to be viewed from the outside, so that the height 60 and condition of the contained hydrocarbon fluid may be readily ascertained, while the upper end of the tube 2 is threaded for connection with a pipe leading to the inlet-passage of the engine or motor. The lower end 65 of the pipe 2 is also preferably threaded for connection with an air pipe or passage leading thereto from any suitable point, but may be left open for the direct entry of air, if desired. It will thus be seen that the tube 2 70 will form an uninterrupted air-passage connecting when the device is attached to a motor to the inlet or suction port of the motor with the atmosphere. An inlet-opening 10 is formed in the cap 3 to maintain atmospheric 75 pressure on the surface of the oil in the reservoir 5.

The bottom cap 4 is provided with passages 11 and 12, communicating with the lower end 80 of the reservoir 5. The passage 11 is designed for connection with a pipe leading from a pump which supplies oil to the reservoir from a suitable supply-tank, while the passage 12 is adapted for connection with a pipe for conveying back to the tank any surplus oil which 85 may be supplied to the reservoir 5. The level of the oil in the reservoir is determined and maintained by an overflow-pipe 13, into which the excess oil flows and is conducted to the passage 12 to be returned to the tank. The 90 tank, pump, motor, and connecting-pipes are not herein shown, as the manner of connecting up these parts will be apparent to those versed in the art.

The oil is supplied to the mixing-chamber 95 from the reservoir through a feed-passage 14, formed in the cap 4, and communicating with this passage is a feed-tube 15, which extends up into said chamber to a point above the level of the oil in the reservoir 5. In the operation of the engine or motor when the piston moves away from the closed end of the cylinder a partial vacuum is formed, which causes the air to rush through the tube 2 and through 100

the passage leading therefrom to the motor-cylinder. By this means a partial vacuum is also created in the air-passage and mixing-chamber 6, which causes a definite quantity 5 of oil to spurt in the form of spray from the tube 15 and commingle with the air, thus producing the explosive mixture. By this mode of feeding the oil the exact amount or proportion to be admixed with the air to form the 10 explosive mixture is supplied and a more thorough and effective commingling of the vapor and air insured, so that a mixture combining the elements in the proper proportions to explode will at all times be conducted to 15 the motor-cylinder. A needle-valve 16 is provided for regulating the flow of oil through the passage 14 and extends through a stuffing-box 17 to the exterior, where it is provided with a hand wheel or disk 18 for adjusting it. 20 This wheel or disk bears upon its outer face the words "Start" and "Run" or suitable marks or indices which coöperate with a hand or pointer 19, extending from the cap 4, to indicate the extent to which the wheel should 25 be turned to regulate the valve to allow the oil to feed fast or slow when starting the motor and when the motor is running at its normal or a given speed. By this means the feed of oil may be correctly and conveniently governed, so as to enable the best results to be 30 obtained.

The use of the glass shell 1 enables the interior of the reservoir or feed-cup to be readily viewed, as before stated, so that a casual inspection will show whether or not the oil is in 35 proper condition for use or the carbureter requires cleaning.

From the foregoing description, taken in connection with the accompanying drawings, 40 it is thought that the construction, mode of operation, and advantages of my improved carbureter will be readily understood without requiring a more extended explanation.

Various changes in the form, proportion, 45 and the minor details of construction may be resorted to without departing from the prin-

ciple or sacrificing any of the advantages of this invention.

Having thus described the invention, what is claimed as new, and desired to be secured 50 by Letters Patent, is—

1. A carbureter for explosive-motors comprising an outer shell, detachable heads closing the upper and lower ends of the shell, the lower head being provided with an inlet-passage, an outlet-passage and an oil-feed passage and having an air-inlet with an upwardly-extending threaded portion, an air-tube concentrically arranged within the shell and forming an air-passage and with the shell an 55 oil-reservoir, said reservoir being in communication with the inlet and outlet passages and connecting with the air-passage through the oil-feed passage, the tube passing through the upper head and having an enlarged upper 60 end to bear upon said head and a threaded lower end engaging the upwardly-extending threaded portion of the lower head, an overflow-pipe in the reservoir communicating with the outlet-passage, a feed-pipe in the tube 65 communicating with the oil-feed passage, and a valve governing the oil-feed passage, substantially as specified.

2. In a carbureter, an outer shell, heads closing the upper and lower ends of the shell, 70 and a tube concentrically arranged within the shell and passing through the upper head, said tube being provided with an enlarged upper end bearing on the outer surface of the upper head and threaded at its lower end 75 to the lower head, whereby the shell is clamped between the heads and the parts held assembled, substantially as and for the purpose set forth.

In testimony whereof I have hereunto set 80 my hand in presence of two subscribing witnesses.

WILLIAM A. GILL.
